HAMMOCK

Filed Sept. 27, 1924

Fig. 3.

INVENTOR.

Jane May Banning
BY
Banning & Banning
ATTORNEY

UNITED STATES PATENT OFFICE.

JANE MAY BANNING, OF HINSDALE, ILLINOIS.

HAMMOCK.

Application filed September 27, 1924. Serial No. 740,182.

To all whom it may concern:

Be it known that I, JANE MAY BANNING, a citizen of the United States, residing at Hinsdale, in the county of Du Page and 5 State of Illinois, have invented certain new and useful Improvements in Hammocks, of which the following is a specification.

This invention is directed primarily to a hammock designed for use as a baby's 10 cradle, although the principles involved are applicable to full size hammocks intended for use by adults. The invention has particular reference to the provision of a depending pocket located at the head end of 15 the hammock, which makes provision for the support and retention of a pillow which will thus be supported in such a manner as to bring its upper surface but slightly above the plane of the body portion of the 20 hammock thereby affording a soft and easy rest for the head without bending the neck upwardly to any appreciable degree.

Furthermore, the arrangement is one 25 which prevents displacement of the pillow and tends to prevent the head from slipping down to one side as is often the case where pillows are employed in hammocks of the ordinary type.

Further objects and characteristics of the 30 invention will be apparent from a detailed description thereof, reference being made to the accompanying drawings wherein—

Fig. 1 is a perspective view showing the hammock in its preferred form;

35 Fig. 2 is a cross sectional view through the depressed pocket looking toward the foot of the hammock and also including the provision of side flaps which are omitted in Fig. 1; and

40 Fig. 3 is a plan view of a modified form of framework.

Referring to Fig. 1, the hammock comprises a body portion A of canvas or other suitable fabric at the head end of which is 45 a depression or pocket B of suitable size and shape to receive a pillow C, and of sufficient depth to bring the surface of the pillow but slightly above the surface of the body portion, as indicated in Fig. 2. It is preferred to form the pocket portion from a continuation 50 of the same section of fabric which constitutes the body portion, although obviously a separate section of fabric might be utilized.

55 The ends of the hammock, as shown in Fig 1, are lapped over and secured to a pair

of spreader rods D to which the suspending cords E are secured in the usual manner. The sides F of the hammock are lapped over and secured around a pair of side supporting cords G, and, if desired, the fabric can be further extended on each side to afford side flaps H which are provided with suitable fasteners I, and which may be, if desired, lapped over the top of the hammock 60 and secured to prevent displacement of blankets or covers laid over the occupant of the hammock. As indicated, in Fig. 3, in lieu of the spreader rods D and connecting cords G, a rigid wire framework J of rectangular form comprising sides K and ends L may be employed.

If desired also a pillow strap M secured to head end of the hammock may be provided which is lapped over the pillow and 70 secured by buttoning or otherwise at the point N.

As shown, it is preferred to have the fabric of the body portion sufficiently loose to sag down slightly, as indicated, but the 80 head pocket will depend considerably below the sagged down center of the body, so that when the head of the occupant rests upon the pillow, the pillow will be crushed down slightly to bring the back of the head substantially on a level with the body of the 85 hammock, so that an easy and natural position will be maintained. Of course, the actual position occupied by the head will depend in considerable measure upon the size 90 and degree of softness of the pillow which obviously may be varied to meet the desires or inclinations of the user.

In hammocks of the ordinary character, 95 where an attempt is made to employ a pillow, there is a natural tendency when the hammock is subjected to the weight of the occupant for the pillow to slide down towards the longitudinal center of the hammock and also for the pillow to be displaced 100 to one side or even fall out of the hammock unless secured in place in some way. At the same time there is a natural inclination for the head of the occupant to slide down from the pillow which presents an inclined elevated surface, and these tendencies are noted particularly in the case of 105 small hammocks intended for babies and children, who are not willing or able to maintain a proper position.

In the hammock of the present invention, 110 the pillow is socketed within the pocket in

such a way to prevent either longitudinal or lateral displacement, and the low position of the head which will lie within a depression naturally formed within the pil-
5 low surface, will not only tend to afford an easy and more comfortable position and thereby reduce any wish or inclination to shift the position, but will also tend to positively prevent such shifting or any sliding
10 or sagging down of the body toward the longitudinal center of the hammock.

The strap M may prove of advantage, in some circumstances, in retaining the pillow in position where it is desired to roll up
15 the hammock into a small compass, but will ordinarily be unfastened and hang down when the pillow is in service.

The invention is one which is peculiarly fitted for use as a child's cradle and possesses special and particular advantage for use in automobile touring. When used for touring purposes, the provisions made for preventing any displacement of the child's head or body or for preventing slipping or
25 falling from the hammock will prove of peculiar value especially when the hammock is subjected to the strain and rolling action of a car on a rough highway. Furthermore, the ease with which the hammock
30 and pillow may be rolled up into a small compass, fit the device peculiarly for touring service.

I claim:

1. A hammock composed of fabric and comprising a comparatively flat body portion merging uninterruptedly at one end into a comparatively deep pocket portion configured to receive and retain a pillow, the material composing the pocket being
35 given the necessary fullness to bag downwardly in the center and being upturned at the sides of the hammock to align with the side edges of the body portion, and the
40

base of the pocket being below the level of the base of the adjacent body portion of
45 the hammock, and the pocket downwardly extending directly from the base level of the body portion when the hammock is suspended in a substantially horizontal plane, and a rigid cross spreader at each end of
50 the hammock to which the outer ends of the body portion and pocket are respectively secured and from which the hammock is suspended, the space between the cross
55 spreaders being unobstructed by rigid cross supports, substantially as described.

2. A hammock composed of fabric and comprising a comparatively flat body portion merging uninterruptedly at one end into a comparatively deep pocket portion
60 configured to receive and retain a pillow, the material composing the pocket being given the necessary fullness to bag downwardly in the center and being upturned at the sides of the hammock to align with the side edges of the body portion, and the base of the pocket being below the level of
65 the base of the adjacent body portion of the hammock, and the pocket downwardly extending directly from the base level of the body portion when the hammock is suspended in a substantially horizontal plane, a rigid cross spreader at each end of the
70 hammock to which the outer ends of the body portion and pocket are respectively secured and from which the hammock is suspended, the space between the cross
75 spreaders being unobstructed by rigid cross supports, and a suspending cord extending in an undeflected line along each side of
80 the hammock, said cords being connected at their ends to the ends of the cross spreaders and having the side edges of the body portion and pocket secured thereto, substantially as described.

JANE MAY BANNING.
